UNITED STATES PATENT OFFICE

2,178,677

CARBURETOR

Ormsby P. Williams, Huntington Park, Calif.

Application August 31, 1937, Serial No. 161,783

5 Claims. (Cl. 261—49)

An object and feature of my invention in a carburetor is in the simultaneous control of the jets of liquid fuel such as gasoline and the air flow through the atomizing or vaporizing part of the carburetor so that the suction caused by the flow of air will not only cause the flow of the liquid fuel from for instance a float chamber bowl of the carburetor, but will also cause the rapid vaporization and complete mixture of the fuel and the air. Another object and feature of my invention is employing a centrally positioned rotary type of valve for the liquid fuel in which fixed inner ports operate with ports on a rotatable sleeve so that these may be aligned in the desired degree to control the flow of the liquid fuel substantially radially outwardly through the valve. In conjunction with this the valve is positioned directly in the center of the main air flow so that the radially jetting liquid fuel is incorporated in the flow of air.

Another object and feature of my invention is the combination of the central jet valve discharging the jets of fuel radially in conjunction with rotary air valves positioned at the inlet and outlet of the carburetor and preferably such valves being connected by a Venturi type of tube, thus the throat of the venturi is substantially in alignment with the radial jets from the fuel valve. The Venturi tube with a tube having the cone type of air valves is connected to the sleeve of the jet valve so that all of these are rotated simultaneously and the same amount to thereby regulate the air inlet, the fuel jets and the outlet from the carburetor of the mixed fuel.

Another characteristic of my invention is in employing a down draft type with the jet valve for the liquid fuel arranged centrally of the valve housing in the rotatable Venturi tube, this being stream-lined to develop a non-turbulent flow of air over the valve and thereby carry the liquid fuel in the air stream. The sleeve of the air valve is connected by a radial rod to a control which operates through a slot in the carburetor housing and thus as the arm may be moved in an arcuate motion, there is a simultaneous control and movement of the jet valve and the air inlet and outlet valves. An additional feature of my carburetor includes an auxiliary air inlet connecting in the carburetor housing between the jet valve and the outlet valve for the mixture.

My invention is illustrated in connection with the accompanying drawings, in which:

Fig. 1 is a vertical section which may be con-

sidered as taken on the section line 1—1 of Figs. 4 or 5 in the direction of the arrows.

Fig. 2 is a side elevation taken in the direction of the arrow 2 of Fig. 4 or 5.

Fig. 3 is an elevation similar to Fig. 2 with certain control parts removed to show the movement of the valve control arm.

Fig. 4 is a horizontal section on the line 4—4 of Fig. 1 in the direction of the arrows illustrating the liquid jet ports and the outlet mixture valve.

Fig. 5 is a transverse section on the line 5—5 of Fig. 1 in the direction of the arrows illustrating part of the inlet air valve.

Fig. 6 is a vertical detail being an interior elevation on the line 6—6 of Fig. 1 in the direction of the arrows of the auxiliary air inlet valve showing the ports.

Fig. 7 is a vertical section on the line 7—7 of Fig. 1 in the direction of the arrows through the fuel jet valve.

Fig. 8 is a detail transverse section of the liquid fuel feed tube, on the line 8—8 of Fig. 1.

Fig. 9 is a detail section on the line 9—9 of Fig. 4 being a cross section of the radial arm operating the liquid valve.

The assembly for the set up illustrated of a down draft carburetor I employ a valve base or support 11 which connects to the intake manifold of an internal combustion engine. This has a contracted throat 12 with flanges 13 on the outside, an expanded intake valve end 14 with outside flanges 15 and a cone shaped valve seat 16 which has a series of fixed segments 17 of which I illustrate three having radial side edges 18 converging towards the center and defining with the radial edges the peripheral edge 20, somewhat triangular shaped fixed ports 21. There is a central opening 22 to accommodate the lower end of the liquid jet valve hereinunder described.

The main features of the main air and mixed fuel valve 25 include a cylindrical housing 26 having lower flanges 27 bolted to the flanges 15 and upper flanges 28, bolted to the seat member 30 of the upper valve. Such seat member has a tube 31 and flanges 32 connected to the flange 28 by bolts 33. The upper conical seat 35 is provided with three ports 36, note Fig. 5, defined by the outside peripheral edge 37, the two radial edges 38 and the inner circular edge 39. There is also a central circular opening 40.

The housing cylinder 26 is provided with a circular perforation 45 on one side for the inlet of the liquid fuel supply and with a circular

auxiliary air port 46 shown diametrically opposite, note Figs. 1 and 6. There is also a horizontal slot 47 in the housing, this being indicated as terminating at the ends 48 and 49, note Figs. 2, 3 and 4, there being an enlargement 50 in the slot.

The inner member of the valve 25 designated by the assembly numeral 60 employs a rotatable sleeve 61 which is a cylinder and fits in the inside of a cylinder 26. This cylinder is provided with lower and upper ends 62 and 63 transverse to the axis and having projecting pins 64. Fitted on the lower pins there is the complementary cone valve 65 at the bottom which bears against the fixed valve seat 16 having the ports 21. At the top there is a complementary valve 66 fitted on the upper pins and having a valve action on the underside of the upper conical seat 35. Each of these has three ports complementary to the ports 21 at the bottom and 36 at the top and each has a central opening indicated at 67 as to the top valve member. A liner 70 is fitted inside of the sleeve 61. This forms a venturi with the throat indicated at 71. There is a side opening 72 with a threaded recess 73 in the Venturi, the threaded recess continuing through the sleeve 61 as indicated in Fig. 4.

The liquid jet valve designated by the assembly numeral 85, note particularly Figs. 1, 4 and 7, employs a liquid supply pipe 86 which as to the portion inside of the valve is streamlined in cross section as indicated in Fig. 8 and extends through the opening 45 in the housing and through an internal slot 87 in the sleeve 61. The outer end has a saddle 88 attached to the outside of the housing 26 and is provided with a threaded nipple 89 connected to the float chamber 90 of the carburetor. This float chamber is additionally supported by a bracket 91 attached to the cylinder 26 of the valve housing. The float chamber may be of any suitable type and is provided with a feed connection 92 for the supply of gasoline or the like.

At the inner end of the pipe 86 there is a valve hub 95 with a vertical cylindrical bore 96 therethrough and upper and lower shoulders 97 and 98. A stationary hollow valve stem 100 has a base 101 centered by a pin 101' seated on the upper shoulder 97, a lower hollow projection 102 extending through the bore 96 and a threaded plug end 103, a nut 104 being threaded on this end and holding the hollow stem in a fixed position. An inlet opening 105 communicates with the bore of the liquid supply pipe 86 which supports the valve. The hollow stem is preferably made with a tapered section 106 and a cylindrical section 107 therebelow. There is also an upper cylindrical rim portion 108 interiorly threaded. A plurality of fine ports 109 are spaced peripherally around the cylindrical section 108. These ports may be in the form of narrow slits, the long dimension being circumferential. An adjusting plug 110 is threaded in the upper end and has a screw driver kerf 111. The purpose of this plug is to adjust the area of the ports 109 by cutting off a portion adjacent the top. Manifestly such ports may be of many suitable shapes but are preferably all placed in the same diametrical plane as regards the axis of the hollow stem 100.

The outer or movable part of the valve includes the valve sleeve 115. This has a cylindrical upper section 116, a tapered portion 117 and a cylindrical opening 118 at its lower end. This is assembled on the hollow stem 100 by being

fitted over the lower end prior to attachment to the hub 95 and there is a close riding fit between the opening 118 and the cylindrical exterior 107 of the hollow stem. The cylindrical portion 116 at the top has a plurality of ports 120, these being complementary to the ports 109 and may be in the form of slits with their long measurement circumferential. If desired these slits may have slightly greater measurements as to the vertical height and circumferential length than the ports 109. In the illustration these are both shown exaggerated.

A closure cap 125 has a stream-lined nose structure 126 provided with a shoulder 127 fitting the cylindrical upper end 116 of the sleeve 115 and being attached thereto by screws or the like. This has a central bore 128 and a recess 129 in which is located a compression spring 130 which exerts a pressure between its seat in the cap and the adjusting plug 110. A removable plug 131 fits in a threaded recess at the upper end of the bore 128. This may be removed by a screw driver without disassembling the carburetor. The plug 131 is preferably made of magnetizable metal so that it may be removed by a magnetized screw driver but any suitable tool may be employed. This allows a special adjusting tool to be inserted through the bore 128 to engage in the screw driver kerf 111 and thereby adjust the plug 110 to regulate the area of the ports.

This liquid jet valve is in a sense the equivalent of the throttle of the ordinary type of carburetor and has the features of regulating the jet openings as well as regulating the flow of air. The throttle arm assembly 135 employs a rigid arm 136 (note Figs. 4, 7 and 9). This is attached as by welding or the like indicated at 137 to the sleeve 115 and passes outwardly through the side opening 72 of the liner 70 and the sleeve 61. It fits in an outer tubular arm 138 which has a threaded head at 139, such head being threaded in the recess 73 of the liner 70 and the sleeve 61. This head makes an air tight closure. The outer portion 140 of the tubular arm operates in the slot 47 in the cylindrical housing 26. The purposes of the enlargement 50 is to accommodate the head 139 in assembling this with the sleeve and liner and disconnecting the same. A radial arm 141 fits in the tubular arm 138 and has a ball type of link 142 connected thereto at the outside. This has a pivotal connection 143 to a bell crank 144, the connection being to the arm 145. The bell crank is pivoted at 146 (note Fig. 2) to a lug 147 attached to or formed integral with the sleeve 26. The other arm 148 of the bell crank is pivotally connected to a throttle link 149 leading to a throttle control pedal or the like. Thus on a reciprocating motion of the link 149, a pivoting action is communicated to the bell crank 144 and this produces an arcuate movement of the throttle arm assembly 135 in the slot 47, the limit of movement being between the ends 48 and 49 of the slot.

However, it is desirable to have a limiting stop to the movement of the throttle arm assembly, therefore I utilize a stop limit device 155 (note Figs. 3 and 4). This employs a bracket 156 attached to the fixed housing sleeve 26 having a threaded end portion 157 with an adjusting screw 158 threaded therethrough. This screw may have a lock nut and the end of the screw engages the tubular arm 138 limiting its arcuate movement and hence the amount of movement of the

liquid valve assembly 85, that is, the movement of the sleeve of such valve.

The auxiliary air supply device designated by the assembly numeral 165 employs an air inlet tube 166 (note particularly Figs. 1, 2 and 6). This has a saddle 161 connected to the cylinder 26 and surrounding the circular port 46 in this cylinder. A rotating valve 168 includes a valve shaft 169 and a damper plate 170, the shaft being rotatable on opposite sides of the air inlet tube 166. A rotatable operating rod 171 has a universal joint connection 172 to the shaft 169. This rod leads to the operator's compartment of a vehicle if the carburetor is used in a vehicle or to any suitable location. A stop arm 173 and a stop pin 174 indicate the position of the valve when full open or if desired the position when closed. A characteristic of the auxiliary air inlet resides in the port 180 in the sleeve 61. This as shown in Fig. 6 has a V shaped portion 181 with the apex 182. The sides of the V are tangent to the circular opposite end 183. Thus when the apex of the V or the portion adjacent thereto overlap the circular port 46 and the valve 168 is open, only a small amount of additional air may enter the carbureting chamber, this being formed inside of the sleeve 61, however when the sleeve is rotated a greater distance the large end indicated at 183 may align with the circular opening 46 and thus give a large opening for the auxiliary air.

An ordinary choke valve assembly 190 has an air inlet tube 191 connected to the upper end of the tube 31 and is provided with the ordinary damper type of choke valve designated 192, this being operated by a crank 193 secured to the shaft and having a Bodin wire assembly 194 with the moving wire connected to the outer end of the crank. The limit of movement is controlled by a radial arm 195 engaging a stop pin 196 (note Fig. 2).

The manner of operation and functioning of my invention is substantially as follows: in starting an engine it is desirable to have the auxiliary air supply valve 168 closed and the choke 190 may be opened or closed at the discretion of the operator. The manipulation of the throttle by the operator is the same as any standard carburetor and used in a motor vehicle is usually by a foot throttle lever. As above mentioned, this action moves the throttle arm assembly 135 through an arcuate motion. In view of the fact that the cylindrical housing 26 is stationary and the hollow valve stem 190 is also stationary, there is a simultaneous rotational movement of the valve sleeve 115 of the liquid valve 85 which regulates the registry of the ports 120 in the sleeve with the fixed ports 109 of the hollow stem 168. Also on account of the throttle arm assembly which has the arm 136 and the tubular arm 133 and this latter is connected to the sleeve 61 and the liner 70, there is a simultaneous rotation of this sleeve and the liner which action carries in rotation the lower complementary parts 65 of the lower cone valve operating on the seat 116 and the upper complementary cone 66 operating in connection with the upper cone valve having the upper seat 35. There is therefore a complementary change of the size of the air openings or ports for the downflow of air past the choke into the venturi construction and the outflow of the mixture through the lower cone valve assembly, this leading to the throat 12 which is connected to the intake manifold of the engine. The area of the air openings

in the upper and lower cone valve are proportioned to the amount of liquid fuel such as gasoline that can flow through the ports 109 and 120 of the liquid valve 85. As above mentioned the effective area of the ports 109 may be regulated by adjusting the plug 110 upwardly or downwardly in the upper part of the stem 106 in order to obtain the correct amount of liquid fuel from the amount of air used in carbureting and supplied to the engine.

The liquid fuel jets discharge radially and I employ a sufficient number of these to have a distribution of liquid fuel spread in the throat 11 of the venturi. At this area or section the air has its highest velocity downwardly and thus readily breaks up and absorbs the liquid fuel. It will be noted that the valve assembly 85 is carefully stream-lined in order to induce a smooth surface flow of air over the outside of this valve and over the supporting base 95. In order to add additional air the valve 168 may be opened and thus additional air is drawn into the chamber above the lower cone valve. This is regulated by the valve ports 46 and the somewhat V shaped port 180 in the sleeve 61 and therefore gives a correct proportioning of the additional air in accordance with the requirements of the engine.

It is to be understood as above mentioned, that either the ports 109 or 120 of the jet valve 30 may be of shapes other than elongated slots or fine slits. For instance they could be somewhat triangular or arranged to have a series of perforations of which a variation in number aligning would give increased openings. A characteristic of my type of fuel valve is that this does not develop any of the so-called "flat spots" in carburetion which is due to the pump from the operation of one jet to that of another or an increase or decrease of jets. With my valve 40 using the slots or slits, there is a continuous enlargement or decrease in the size of the openings.

It is to be understood that my liquid fuel valve will operate substantially equally well as a gas valve where the supply of fuel is either manufactured or natural gas. It is quite common in such type of gas engines to start these using gasoline or similar fuel and then when the engine is properly heated to cut off the liquid fuel and transfer to the gaseous fuel. It will be seen that this may 50 be readily done with my invention.

Various changes may be made in the details of the construction without departing from the spirit or scope of the invention as defined by the appended claims.

I claim:

1. A carburetor comprising in combination an air flow valve including a housing with an inside cylindrical surface and having a cone type of valve element connected thereto, a cylindrical sleeve mounted for rotation in the housing and having a complementary cone valve element connected thereto, said elements having ports for registry, a liquid fuel valve including a hollow stem, means to retain said stem in a fixed position aligned with the axis of the said sleeve, a pipe connection to the stem for liquid fuel, a sleeve rotatably mounted on the hollow stem and having a closure cap at the end of the hollow stem, the hollow stem and the sleeve mounted thereon 70 having complementary ports, a throttle arm connected to the sleeve of the liquid valve and also connected to the sleeve of the air valve having a slot, a secondary throttle arm connected to the sleeve of the air valve and extending through 75

the latter slot whereby an arcuate movement of the secondary throttle arm in the said latter slot develops a rotational movement of the air valve sleeve and the sleeve of the liquid valve, thereby producing a simultaneous action of the liquid valve and the cone type of air valve.

5. A carburetor as claimed in claim 1, the hollow stem having an adjustable plug mounted therein located inside of the closure cap, said closure cap having a bore with a removable plug whereby on removal of such plug the adjustable plug may be moved, the said adjustable plug being positioned to regulate the effective size of the ports of the hollow stem.

10. 6. A carburetor as claimed in claim 1, an auxiliary air supply means including an air tube connected to the housing and having a valve mounted therein, said housing having a port at the end of the air tube and the sleeve of the air 15 valve having a complementary port whereby the rotation of the air valve sleeve in the housing regulates the registry of the ports of the auxiliary air supply means.

15. 7. A carburetor comprising in combination an air valve structure having a fixed housing cylindrical on its inside surface and having upper and lower cone type of air valve with fixed lower and upper seat elements connected to the housing, an air valve sleeve cylindrical on its outside surface and mounted for rotation in the housing and having complementary upper and lower air valve elements to engage the seat elements, the said air 20 valve elements having ports for registry, a liner

in the said sleeve having a throat forming a venturi, a liquid fuel valve including a hollow stem, a supporting means to position the stem in a fixed position and in the axial line of the said housing, there being a fuel supply means to the hollow 5 stem, a second sleeve mounted for rotation on the hollow stem, complementary ports in the hollow stem in the second sleeve, an adjusting plug in the hollow stem to regulate the effective opening of the ports of said stem, a closure cap connected to the second sleeve and forming a cover for the end of the hollow stem and the adjustable plug, the said closure cap and the second sleeve having a stream-lined contour and positioned substantially in the throat of the venturi 10 with the ports of the liquid valve discharging into said throat, a rigid connection between the first and second sleeves for simultaneous rotation thereof, means to rotate the first sleeve on its axis and hence rotate the second sleeve of the 15 liquid valve and thereby conjointly regulate the registry of the ports of the liquid valve and the upper and lower ports of the air valve.

20. 8. A carburetor as claimed in claim 4, an auxiliary air supply means including an auxiliary 25 air valve connected to the said housing, said housing having a port, the first sleeve having a complementary port, one of said latter ports being of a non-symmetrical shape as regards the other port to develop a variable opening on the 30 rotation of the first and second sleeves in relation to the housing.

ORMSBY P. WILLIAMS.
